UNITED STATES PATENT OFFICE.

HENRY V. FARIES, OF ATCHISON, KANSAS, AND CHARLES D. WILCOX, OF INDIANAPOLIS, INDIANA.

BOILER-CLEANER.

SPECIFICATION forming part of Letters Patent No. 352,235, dated November 9, 1886.

Application filed July 31, 1886. Serial No. 209,666. (No model.)

To all whom it may concern:

Be it known that we, HENRY V. FARIES, a citizen of the United States, residing at Atchison, in the county of Atchison, State of Kansas, and CHARLES D. WILCOX, a citizen of the United States, residing at Indianapolis, in the county of Marion and State of Indiana, have invented a new and useful Improvement in Boiler-Cleaners, of which the following is a full, clear, and exact description, such as will enable any one skilled in the art to which it appertains to make and use the same.

Our invention relates to that class of boiler-cleaners in which the impurities in the water are skimmed from the surface and conducted into a settling-drum, from which they may be blown out, the cleaned water being returned to the boiler.

The object of our invention is to accomplish the removal of the impurities in a more effectual and thorough manner than heretofore; and to this end our invention consists in an improved skimming device, as hereinafter described, and particularly pointed out in the claims.

In the drawings accompanying this specification, and forming a part thereof, and in which like letters refer to like parts in both the figures, Figure 1 is a longitudinal section of our invention applied to a boiler. Fig. 2 is a cross-section of the boiler on the line *x y*, Fig. 1.

A is a boiler, having the ordinary flues, *B*. Just above the flues, and submerged below the level of the water, is a pipe, *C*, closed at each end and extending nearly across the boiler. Projecting from this pipe are several small tubes, *D D*, which are preferably inclined, as shown. Each of these tubes is closed at its upper end, and is perforated with a number of small holes, *d d*, distributed over its entire surface. The tubes are of such a length as to project above the surface of the water into the steam-space. They may be arranged in one, two, or more rows, and may be disposed opposite to each other, or staggering, as deemed most desirable, the object being to enable the skimming to be done over as wide a range as possible, both vertically and laterally. The tubes *D D* extend upward some little distance from the pipe *C*, in order that

at the differing heights of water in the boiler they may always afford an outlet for the impurities floating on the surface. An eduction-pipe, *E*, leads from the submerged pipe *C* up through the top of the boiler to the drum *F*, 55 and is provided with a valve, *e*. An ejector-pipe, *G*, whose upper end, *g*, is located well above the water-level in the boiler, so as to communicate constantly with the steam-space, enters the pipe *C* and terminates just below 60 the lower end of the eduction-pipe *E*. From the upper part of the drum *F* the return-pipe *H*, controlled by the valve *h*, runs down into and nearly to the bottom of the boiler. The blow-off pipe *I*, provided with a valve, *i*, connects with the lower part of the drum *F*. 65

The operation of our apparatus is as follows: When the valve *e* is opened, the steam enters the upper perforations in the tubes *D D*, and produces an upward flow of steam and 70 water through the eduction-pipe *E*. This is greatly accelerated by the dry steam, which enters the ejector-pipe *G* at *g* and discharges into the lower end of the eduction-pipe *E*, carrying up through said pipe the water and 75 the impurities which have entered pipe *C* through the perforations *d d* in the tubes *D D*, and at the same time sucking in through said perforations a further supply of water and the impurities which are in the vicinity of the 80 tubes, and creating a current toward the tubes from all parts of the boiler. The impurities settle in the drum *F*, from which they can be blown out through the pipe *I*, the cleaned water being returned to the boiler through the 85 pipe *H*. This operation removes from the boiler all foreign and injurious matter, our arrangement of the perforated tubes *D D*, together with the ejector-pipe *G*, giving better results than any other device of which we are 90 aware.

Having thus described our invention, what we claim, and desire to secure by Letters Patent, is—

1. In a boiler-cleaner, the skimming device 95 herein shown and described, consisting of the pipe *C* and the upwardly-inclined perforated tubes *D D*, substantially as and for the purpose set forth.
2. In a boiler-cleaner, the skimming device

herein shown and described, consisting of the pipe C, the upwardly-inclined perforated tubes D D, and the ejector-pipe G, substantially as and for the purpose set forth.

5 3. In a boiler-cleaner, the combination, with a boiler, of a submerged pipe, C, and a series of upwardly-inclined perforated tubes, D D, arranged to project above the surface of the water, substantially as and for the purpose set forth.

10 4. In a boiler-cleaner, the combination, with a boiler, of a submerged pipe, C, closed at each end, a series of upwardly-inclined perforated tubes, D D, closed at their outer ends, an eduction-pipe, E, and an ejector-pipe, G, communicating with the steam-space and terminating just below the lower end of the eduction-pipe, substantially as and for the purpose set forth.

5. In a boiler-cleaner, the combination, with 20 a boiler, of a submerged pipe, C, and one, two, or more rows of perforated tubes, D D, upwardly inclined in opposite directions from each other, so as to operate over a large surface of the water, substantially as and for the 25 purpose set forth.
